UNITED STATES PATENT OFFICE

ADOLPH G. LOTTER, OF MILWAUKEE, WISCONSIN, ASSIGNOR TO H. C. MILLER CO., OF MILWAUKEE, WISCONSIN

RING BINDER

Application filed November 18, 1927. Serial No. 234,107.

This invention relates to ring binders.

In ring binders as heretofore constructed it is the usual practice to provide a spring clip extending the full length of the binder and provided with movable members carrying the half ring sections so that they may be either snapped open or snapped closed.

Other types of binders have been proposed, such as shown in the copending application of H. C. Miller, for visible record system, filed in the United States Patent Office, December 10, 1925, Serial No. 74,523, and now matured into Patent No. 1,787,755. In this latter type of binder, means have been provided for sliding one set of half ring sections with reference to the other set thereof. However, this form of binder is adapted for a direct inward motion of the ring sections and does not employ the spring type, as described immediately above.

This invention is designed to provide a spring type of ring binder which is so constructed that the half ring sections may be shifted longitudinally so as to bodily shift the sheets carried thereby one-half space with reference to the opposite rings, thus permitting the sheets to be turned over onto the opposite rings and transferred in a shifted position, as described in detail in the above identified copending application.

Further objects are to provide a very simple type of spring binder which is so constructed that the shiftable half ring sections may be very readily attached thereto and permitted to shift when the binder is open and to provide a construction which is easily produced, which is easy to operate, and which is reliable in operation.

An embodiment of the invention is shown in the accompanying drawings in which:

Figure 1 is a view of the central portion of the binder with the covers, which are only partially shown, laid out flat;

Figure 2 is an end view of the structure shown in Figure 1;

Figure 3 is a detail showing the manner in which the back is fastened to the spring portion of the binder;

Figure 4 is a view corresponding to Figure

1 showing the rings open and shifted a half space;

Figure 5 is a sectional view on the line 5—5 of Figure 4;

Figure 6 is a detail of the end structure 55 of the binder showing the clip for retaining the slide in either of two positions.

Referring to the drawings, it will be seen that the binder comprises an arcuate spring member 1 (see Figures 2 and 5) which is provided with inturned ends 2 and 3. The in-turned ends receive the rocking plates 4 and 5. One of the rocking plates, for instance, the plate 5, has rigidly attached thereto the ring carrying plate 6. The other ring carrying plate 7 is slidably carried by the plate 4, as will hereinafter appear. The plate 6 carries the half ring sections 8 and the plate 7 carries the half ring sections 9. The binder is adapted to be snapped open or closed by pulling upon the half ring sections 8 and 9. There is a toggle action secured by the arcuate spring 1 and the plates 4 and 5, as is obvious from reference to Figures 2 and 4. Preferably, the ends of the rings 8 and 9 are 75 provided with interengaging notched and projecting portions to secure a positive interlock when the rings are closed.

The plate 7, as may be seen from Figures 1 and 4, is provided with a plurality of slots 80 which are slidably carried by the headed studs 11 secured to the plate 4, thus permitting free longitudinal sliding of the strip or plate 7. This plate 7 is provided with a manipulating handle 12 adjacent one end and is provided with an aperture 13 adjacent the other end.

The aperture 13 is adapted to receive the rounded projecting portion 14 of a spring 15 secured to the plate 4, as shown particularly in Figure 6. This engagement 90 of the aperture and projecting portion 14 is secured when the plate 7 is slid upwardly as viewed in Figure 4. When the plate 7 is slid downwardly, as shown in Figure 1, the projecting portion 14 snaps upwardly 95 beyond the end of the plate 7 and thus temporarily locks it in closed position. The plates 4 and 5 are each provided with notches which receive the contracted portions of headed studs 16, as shown in Figure 5. 100

These headed studs constitute therefor the bearing portions of the plates 4 and 5 and permit the toggle action referred to, and as best shown in Figure 5, the depth and width 5 of the annular channel forming the contracted portion of each stud 16 is such that when the binder is open as illustrated in Figure 5, the edges of the notches in which the contracted portions of the headed studs 10 are received, co-act with the top and bottom of the annular channels forming said contracted portions to prevent movement of the plates 4 and 5 beyond a predetermined degree and to thus retain the plates assembled 15 with the spring back.

A very simple means is thus provided whereby the spring ring type binder may be used for shifting the record sheets as heretofore described without any cumbersome construction whatsoever, but instead in a very 20 cheap and simple manner.

Further it is to be noted that the additional features cooperate with the ring type binder to secure the shiftable features without, however, sacrificing any of the securities of attachment of the parts or the interlocking of the half ring sections. The spring stop 14 arrests the motion of the shiftable plate 7 carrying one half of the ring sections at either of two predetermined points to thus insure correct spacing or correct registry of the rings, so that the binder may be used in the ordinary capacity of a spring type ring binder and also may be used for shifting the sheets.

It is to be noted also that this binder may be very readily attached to a back by the construction illustrated in Figures 1 and 3. This is secured by providing an extra plate 17 having upstruck tongues 18 passing through slots 19 in the bottom of the spring 1 and clamped downwardly in place. These tongues pass through the back 20 and the entire back is covered with suitable fabric in 45 accordance with the usual practice, such fabric being omitted from Figure 3 for the sake of clearness.

These tongues are preferably made of triangular shape, as shown particularly in Figure 1, and the plates 5 and 6, and 4 and 7, are provided with cutouts 21 and 22, which register, as shown in Figure 1, and permit a clinching or riveting tool to be passed therethrough. Further than this, the plates 6 55 and 7 are provided with cutout portions 23 and 24 to accommodate the heads of the studs 16, as shown most clearly in Figures 1 and 4. The cutout 24 is elongated to provide space for the shifting of the plate 7.

It will be seen that a very simple type of spring ring binder has been provided which not only has the characteristics of the spring type binder but also provides for the shifting of one set of prongs with reference to the other set of prongs.

Further, it will be seen that none of the security of attachment attained by the ring type binder is sacrificed by this invention, but that instead all of the desirable features of this ring type binder have been retained and the cooperative shifting features have been also obtained by this invention in addition to the points enumerated above.

Although the invention has been described in considerable detail, such description is intended as illustrative rather than limiting as the invention may be variously embodied and as the scope of such invention is to be determined as claimed.

I claim:

1. A ring binder comprising a back including an arcuate shaped spring member, sidewise adjacent toggle plates connected at their outer edges with the spring member, means engaging the adjacent edges of the toggle plates to form a rocking connection therebetween, said means maintaining the toggle plates assembled with the spring member, a series of rigidly mounted half-ring sections carried by one of said toggle plates, a slidably mounted plate carried by the other toggle plate, and a series of half-ring sections carried by the slidably mounted plate.

2. A ring binder comprising a back, an arcuate shaped spring member carried thereby, toggle plates disposed side by side with their opposite edges connected with the spring member, means engaging the adjacent edges of the toggle plates to provide a rocking connection therebetween, said means maintaining the toggle plates assembled with the spring member, a series of rigidly mounted half-ring sections carried by one toggle plate, a slidably mounted plate carried by the other toggle plate, a series of half-ring sections carried by said slidably mounted plate, and means for holding said slidably mounted plate in either of two positions with reference to the corresponding toggle plate.

3. A ring binder comprising yieldably mounted toggle plates, one of said toggle plates having rigidly mounted half-ring sections, the other of said toggle plates having a slidably mounted plate, means retaining the toggle plates in operative association and including a spring member yieldably retaining the toggle means in either of two positions with their inner adjacent marginal edges above or below an imaginary horizontal line traversing their outer marginal edges, and a plurality of half-ring sections carried by said slidably mounted plate.

4. A spring ring binder comprising a body portion, an arcuate shaped spring member carried thereby, a pair of toggle plates arranged side by side and having their opposite edges connected with the spring member, means engageable with the adjacent edges of said toggle plates for maintaining the same in alignment and preventing de-

tachment of the plates from the spring member, a series of half-rings carried by one of the toggle plates, a slidable plate carried by the other of said toggle plates, a plurality of half-rings carried by the slidable plate and adapted to cooperate with said first-mentioned series of rings, and a handle member carried by said slidable plate whereby it may be shifted to stagger its series of half-ring sections with reference to the other series.

5 5. A visible record binder of the spring ring type comprising a back having cover portions connected with its marginal edges, an arcuate spring member carried by the back and having its longitudinal marginal edges flanged inwardly to form channels, elongated plates, the combined width of which is greater than the width of the spring member, said plates having their outer marginal edges engaged within the channels of the spring member, means securing the meeting inner marginal edges of the plates against separation whereby through the action of the spring member said plates are held in either a position with their meeting inner marginal edges above or beneath an imaginary line drawn through the channels of the spring member, a set of half rings associated with each elongated plate with their ends so arranged that when the plates are in a position with their meeting marginal edges beneath an imaginary line connecting the spring member channels, loose sheets carried by one set of half rings may be slid thereover onto the other half rings, and means movably mounting the half rings of one set whereby the ends thereof may be offset with respect to the rings of the other set to enable the leaves to be staggered with respect to each other without removing them from the binder.

45 6. A ring binder, comprising a back, an arcuate shaped spring member carried thereby, toggle plates carried by said spring member, one of said toggle plates having rigidly mounted half ring sections, the other of said toggle plates having a slidably mounted plate, means maintaining the toggle plates assembled with the spring member, a plurality of half ring sections carried by said slidably mounted plate, and means for holding said slidably mounted plate in either of two positions with reference to the corresponding toggle plate and including a projection carried by the last mentioned toggle plate and engageable with the slidably mounted plate in either of its positions.

55 7. A snap ring binder comprising two series of half rings, supporting means for the half rings, said supporting means being movable to permit the series of half rings to be moved to and from a closed position with the ends of the half rings engaged, means associated with the supporting means for yieldably retaining the series of half rings

in either closed or open position, and means movably mounting the half rings of one series from its supporting means to enable the outer ends of the two series of half rings to be staggered with respect to each other.

70 8. In a loose leaf binder of the split ring type adapted to contain record leaves, a back member, a pair of opposed plates mounted on the back member, opposed series of spaced half-rings carried on the plates, said plates being adapted to be moved angularly with respect to each other whereby the opposed series of half rings will be moved toward and from each other, and means for moving one series of half-rings longitudinally in relation to the other series to effect longitudinal shifting of leaves with respect to each other.

75 9. In a visible record removable leaf holder, the combination of a back having tilting sections therein, arranged to tilt about parallel axes disposed at the outer longitudinal edges of the back, ring halves on each section, and instrumentalities whereby the ring halves on one section are movable in unison 80 out of alignment with the ring halves of the other section.

85 10. In a visible record removable leaf holder, the combination of a back having tilting sections therein, arranged to tilt about parallel axes disposed at the outer longitudinal edges of the back, ring halves on each section, and instrumentalities whereby the ring halves on one section are movable in unison 90 out of alignment with the ring halves of the other section, said instrumentalities comprising a plate rigid with the ring halves and slidable on said one of said sections.

95 11. In a visible record removable leaf holder, the combination of a back having tilting sections therein arranged to tilt about parallel axes disposed at the outer longitudinal edges of the back, ring halves on each section, and instrumentalities whereby the ring halves on one section are movable in unison 100 out of alignment with the ring halves of the other section, said back being resilient and operative to yieldingly hold the two sections in buckled position either above or below the center when the ring-halves are 105 opened or closed, said instrumentalities comprising a member upon which the ring-halves of one section are mounted and a pin and slot connection between said member and said section.

110 In testimony that I claim the foregoing I have hereunto set my hand at Milwaukee, in the county of Milwaukee and State of Wisconsin.

115 ADOLPH G. LOTTER.
